(57) **CLAIM**

The ornamental design for tablet computing device, as shown and described.

DESCRIPTION

FIG. 1 is a perspective view of the tablet computing device; FIG. 2 is a side view of the tablet computing device; FIG. 3 is a side view of the tablet computing device; FIG. 4 is a front view of the tablet computing device; FIG. 5 is rear view of the tablet computing device; FIG. 6 is a top view of the tablet computing device; and, FIG. 7 is a bottom view of the tablet computing device. The broken lines shown in FIGS. 1,2, and 4-7 illustrate portions of the tablet computing device that form no part of the claimed design.
